PHOTOGRAPHIC SLIDE HOLDER AND EJECTOR

William C. Cassady, Vancouver, Wash.

Application January 20, 1954, Serial No. 405,125

1 Claim. (Cl. 221—276)

This invention relates to a holder and ejector primarily adapted for use in holding a plurality of photographic slides in superimposed stacked relationship and by means of which the slides may be individually ejected from the bottom of the stack.

Another object of the invention is to provide a holder and ejector which is likewise adapted for similarly holding and ejecting other flat articles.

A primary object of the present invention is to provide a holder and ejector of extremely simple construction capable of being very economically manufactured and sold yet which will be extremely efficient and durable and well adapted to effectively accomplish its intended results.

Various other objects and advantages of the invention will hereinafter become more fully apparent from the following description of the drawings, illustrating a presently preferred embodiment thereof, and wherein:

Figure 1 is a front elevational view of the holder and ejector;

Figure 2 is a top plan view thereof;

Figure 3 is a fragmentary vertical sectional view on an enlarged scale, taken substantially along a plane as indicated by the line 3—3 of Figure 1 and showing a number of slides disposed within the holder;

Figure 4 is a horizontal sectional view of the holder and ejector, taken substantially along a plane as indicated by the line 4—4 of Figure 3;

Figure 5 is an enlarged fragmentary vertical sectional view taken substantially along a plane as indicated by the line 5—5 of Figure 2;

Figure 6 is a fragmentary horizontal sectional view, similar to Figure 4 and with the ejector omitted;

Figure 7 is a plan view of a tabbed indexing card;

Figure 8 is a fragmentary transverse vertical sectional view taken substantially along a plane as indicated by the line 8—8 of Figure 3 and with the slides omitted, and

Figure 9 is a perspective view of the ejector element detached from the holder.

Referring more specifically to the drawings, the slide holder and ejector in its entirety and comprising the invention is designated generally 10 and includes an elongated upright holder or magazine, designated generally 11, which is preferably formed of sheet metal of substantially rectangular cross section and which includes a rear wall 12, substantially parallel side walls 13 which are disposed at right angles to the rear wall 12 and a front wall formed of corresponding sections 14 which extend inwardly from forward edges of the side walls 13 and which are spaced apart a substantial distance to provide a relatively wide slot 15 therebetween which extends from top to bottom of the magazine or holder 11. The front wall sections 14 are likewise preferably disposed at right angles to the side walls 13 and substantially parallel to the rear wall 12.

The holder and ejector 10 also includes a relatively thick base member 16 which may be formed of any suitable relatively lightweight material which is of a width

2

substantially corresponding to the width of the holder or magazine 11 as measured between the side walls 13, and of a length from front to rear greater than the distance between the front wall sections 14 and rear wall 12. The side walls 13 have bottom portions 13a extending to below the bottom edges of the rear wall 12 and front wall sections 14 and which engage in recessed portions 17 of the upper portions of the sides of the base 16 and which are secured therein and to the base 16 by suitable fastenings 18. As seen in Figures 1 and 8, the bottom edge of the rear wall 12 rests upon a transverse portion of the top surface 19 of the base 16 and is provided intermediate of its ends with a relatively wide downwardly opening notch 20. The bottom edges of the front wall sections 14 terminate above the level of said top base surface 19 and adjacent the level of the upper edge of the notch 20. The base 16 is provided with an arcuately recessed forward portion 21 disposed beneath the slot 15 and extending from top to bottom thereof.

A pair of substantially flat spacing elements or plates 22 are disposed on the upper surface 19 of the base behind the rear wall 12 and beneath a cover plate 23. Suitable fastenings 24 extend through the cover plate 23 and spacing elements 22 for securing said parts to the base 16. The spacing elements 22 have adjacent ends spaced from one another to form a passageway or guideway 25 which aligns with the central portion of the notch 20. Adjacent inner corners of the spacing elements 22 are provided with notches 26 which open into the ends of the notch 20 and into the inner end of the guideway 25.

An ejector, designated generally 27, includes an elongated substantially flat bar 28 of a width to extend slidably through the guideway 25 and of a thickness to be slidably disposed between the upper surface 19 of the base and the cover plate 23. The ejector bar 28 has a laterally enlarged inner or forward end forming a head 29 which is sized to slide through the notch 20 and the ends of which fit in the notches 26 when said ejector bar 28 is in a normal retracted position, as illustrated in full lines of Figure 4. The bar 28 is provided with a downturned opposite rear end 30 which is normally spaced a substantial distance from the adjacent rear end 31 of the base 16. A disk or plate 32, forming a thumb or finger rest, is secured against the outer side of said downturned end 30 by a rivet or other suitable fastening 33 having a stem or projection 34 extending from the inner side of the bar portion 30. One end of an expansion coiled spring 35 bears against the inner side of said downturned bar portion 30 and engages around and is supported by the stem 34. The other end of the spring 35 seats in a socket 36 which opens outwardly of the rear end 31 of the base.

The rectangular holder or magazine 11 is of a proper cross sectional size to accomodate a stack of photographic slides 37, the bottommost slide of which rests on the upper base surface 19. The holder 11 may be of any height to accommodate any desired number of slides 37, only a few of which have been illustrated in Figure 3, and different groups of slides 37 may be separated by tabbed indexing cards 38 which are likewise sized to fit loosely in the holder 11 and which may contain thereon suitable printed or written information in reference to the individual slides 37 of the group of which the indexing card 38 forms a part. Each indexing card 38, one of which is shown in Figures 3 and 7, includes a tab or extension 39 of reduced width relatively to the width of the card and which projects outwardly through the slot 15, as seen in Figure 3. The individual slides 37 are of a thickness greater than the thickness of the ejector bar 28, as illustrated in Figure 3.

Assuming that the magazine or holder 11 is partially filled or filled with slides 37 and tabbed indexing cards

38, and that the base 16 is resting on any suitable supporting surface, thumb or finger pressure exerted against the plate 32 forwardly or toward the base 16 will cause the ejector bar 28 to slide forwardly from its full line to its dotted line position of Figure 4 to cause the bottom-most slide 37 to be projected forwardly from the bottom of the magazine 11 to its dotted line position of Figure 4. Pressure on the element 32 may then be released allowing the spring 35 to immediately return the ejector bar 28 to its retracted full line position of Figures 3 and 4, in 10 which position the head 29 is disposed externally of the holder or magazine 11. The partially ejected bottom slide 37 may then be grasped between the thumb and index finger with the thumb or finger extending into the recess 21 beneath said bottom slide, for removing the slide from the magazine 11 beneath the front wall sections 14. As the bottom slide 37 is thus withdrawn, the stack of slides 37 and cards 38 will drop downwardly and so that the next lowermost slide 37 will then rest upon the upper base surface 19. As the ejector bar 28 will have been retracted prior to the downward movement of said slides, it will not interfere with the movement thereof and as said bar is of a thickness less than the slides, the next to the bottom slide will not be contacted by movement of the ejector bar 28 to and from its forward projected dotted line position of Figure 4. It will thus be apparent that a holder and ejector or dispenser of extremely simple construction has been provided involving a minimum number of parts which will efficiently function for accomplishing its intended result and which will be extremely durable. It will also be apparent that an indexing card tab 39 may be grasped for removing any group of slides which it is not desired to use. It will also be apparent that each slide after use may be replaced in the magazine 11 through the top thereof for maintaining the slides in a correct order or sequence.

Where glass covered slides are employed, greater spaces may be provided between the top surface 19 of the base and the lower ends of the front wall sections 14 to accommodate the increased thickness of such slides, not shown, and which constitutes the only change required in the holder and ejector 16 for such use.

Obviously, the indexing cards 38 may be ejected when in a bottommost position in the same manner as the slides 37 or may be withdrawn from the magazine 11 by the tab 39 without actuating the ejector 27.

Various modifications and changes are contemplated and may obviously be resorted to, without departing from the spirit or scope of the invention as hereinafter defined by the appended claim.

I claim as my invention:

A holder and ejector for flat card-like elements comprising a relatively thick base having a smooth flat top surface, an elongated upright magazine supported on and rising from said base, said magazine including a rear

wall, a front wall and side walls, said side walls extending below the bottom edges of the front wall and rear wall and having bottom portions straddling a portion of said base and secured thereto for mounting the magazine thereon, said front wall terminating above the top surface of the base to provide a discharge opening, said rear wall having a bottom edge resting on the top surface of the base and provided with an ejector bar receiving notch, said base having a rear portion disposed behind the rear wall of the magazine, a pair of spacer plates disposed on the top surface of the rear portion of the base in spaced apart relation to one another to form a passageway therebetween disposed in alignment with the notch, said notch being wider than said passageway, said spacer plates having notched corners opening into the passageway and into the ends of said rear wall notch, a cover plate overlying the spacer plates, fastenings securing the cover plate and spacer plates to one another and to the base, said cover plate, spacer plates and the rear wall notch combining with a part of the top surface of the base to form a guideway, an ejector bar slidably disposed in said guideway and supported on said top surface for sliding movement longitudinally of the base, said ejector bar including an elongated shank fitting slidably in said passageway and having a laterally enlarged forward end forming a head, said head being of a width greater than the width of said passageway and sized to move slidably through the rear wall notch and to seat in said corner notches of the spacer plates in a retracted position of the ejector bar, said ejector bar being displaceable manually from a retracted position for moving the ejector bar head forwardly through said rear wall notch and into the magazine, spring means urging the ejector bar to a retracted position thereof, said magazine being adapted to contain 25 a stack of card-like elements supported on the top surface of the base, and said ejector bar being of a thickness less than the thickness of the individual card-like elements for engaging and displacing the bottommost card-like element forwardly of the holder and partially through 30 said discharge opening when the ejector bar is manually moved to a projected position.
